UNITED STATES PATENT OFFICE.

GEORGIA S. O'CONNOR, OF MINNEAPOLIS, MINNESOTA.

DESIGN FOR A SCREEN FOR A ROOM.

Application filed April 18, 1927. Serial No. 21,634. Term of patent 7 years.

To all whom it may concern:

Be it known that I, GEORGIA S. O'CONNOR, a citizen of the United States, residing at Minneapolis, in the county of Hennepin and State of Minnesota, have invented a new, original, and ornamental Design for a Screen for a Room, of which the following is a specification, reference being had to the accompanying drawings, forming part thereof, in which:

Figure 1 shows a front elevation of the article showing my new design.

Fig. 2 is a view in side elevation of the device.

What I claim is:

The ornamental design for a screen for a room, as shown.

GEORGIA S. O'CONNOR.
